UNITED STATES PATENT OFFICE.

HERMAN L. GREEVE, OF NEW YORK, N. Y.

MAILING-WRAPPER.

1,071,227.

Specification of Letters Patent. Patented Aug. 26, 1913.

Application filed August 6, 1912. Serial No. 718,616.

To all whom it may concern:

Be it known that I, HERMAN L. GREEVE, a citizen of the United States, and a resident of New York, borough of Brooklyn, in the county of Kings and State of New York, have invented certain new and useful Improvements in Mailing-Wrappers, of which the following is a specification.

This invention relates to mailing wrappers, particularly to the type which is rolled into the form of a tube for wrapping articles to be sent by mail or express, such as drawings, photographs, music, etc., which can be conveniently rolled or folded.

15 The principal object of this invention is to provide an opener for the wrapper which is self-contained, accessible, and which is normally out of the way so as not to be accidentally caught or torn.

20 A further object of this invention is to provide an opener which is easily and cheaply manufactured.

In carrying out my invention, I provide adjacent to the gummed portion of the flap 25 of the wrapper and extending underneath of said flap, a strip of material of greater strength than the material of the wrapper. A rounded, preferably circular, aperture is formed in the flap over the edge of this strip 30 of material, exposing this edge while still leaving the entire strip below the outer surface of the flap. The operator can readily insert his finger within the aperture and grasp the edge of the strip, tear the material 35 of the flap above the gummed portion and thus opening the wrapper. With this construction, the outer surface of the flap presents no projecting portions which are liable to become caught and accidentally tear the

40 flap, so as to open the wrapper or be otherwise injured. The circular aperture is very easily made by placing a high stack of the blanks in a drill press and drilling a hole through the stack of blanks simultaneously.

45 Further objects and advantages will appear hereinafter.

In the accompanying drawings, Figure 1 is a perspective view illustrating my improved wrapper as rolled up in the form 50 of a tube. Fig. 2 is a fragmental view illustrating a development of the wrapper and showing the strip of strong material below the gummed portion, the edge of said strip extending across the aperture. Fig. 3 is a 55 view illustrating the development of a modified form of strip and with a slightly dif-

ferent position of aperture. Fig. 4 is a view illustrating another modified form.

Referring to Figs. 1 and 2, the wrapper 1 has a gummed flap 2 to the interior of which adjacent to said gummed portion is attached a strip 3 of stronger material than the material of the wrapper, such as canvas or like material. The strip is preferably formed with diverging edges 4 and an edge 5 extending across an aperture 6 formed in the flap. When the wrapper is rolled up and the gummed portion attached to the body portion of the wrapper, so as to constitute a tube, the strip 3 is retained underneath the flap with the edge 2 below the outer surface of the flap. This edge lies snugly against the body of the wrapper and when it is desired to open the same, the operator inserts his finger into the aperture 6 and grasping the strip by said edge 5, pulls the same and tears the material of the flap along the diverging edges 4.

In the form illustrated in Fig. 3, the strip 3^a is formed substantially rectangular in section and the aperture 6 is placed to one side. The edge 5^a of the strip is retained beneath the flap in substantially the same manner as the edge 5 in the constructions in Figs. 1 and 2.

In the form illustrated in Fig. 4, the strip 3^b extends across the entire width of the flap and is cut so as to conform to the converging edges of the flap. The aperture 6^b is formed symmetrically on the flap as 90 in the constructions of Figs. 1 and 2. The strip is formed narrow in this construction and may be grasped from either edge.

It will be noted that in all of the constructions above described, the entire strip is located below the material of the flap and presents no projecting portions which may become caught to tear the flap accidentally or be otherwise injured. All of these forms are easy to make and assemble, inasmuch as the apertures can be formed by drilling a hole in a large stack of wrappers and the strips may be easily pasted on the inner face of the flaps without necessitating exact positioning with reference to the apertures.

Having thus described my invention, I claim—

1. A wrapper comprising a flap having a gummed portion, a curved aperture of sufficient area to allow the passage of a finger 110 formed adjacent to said gummed portion, and a strip of material extending across said

flap attached to the interior of the same adjacent to said gummed portion, one edge of said strip extending across said aperture, and the entire strip being located below the 5 outer surface of the flap when the wrapper is rolled and sealed and seating against the body of the wrapper.

2. A wrapper comprising a flap having a gummed end portion adapted to be attached 10 directly to the body of the wrapper, said end portion having converging edges, a strip of stronger material than the material of the flap attached to the interior of said flap adjacent to said gummed portion, there being 15 a circular aperture in said flap across which one edge of said strip extends, said strip having diverging edges in the direction of the converging edges of said gummed portion.

3. A wrapper comprising a flap having 20 converging edges, said flap having a gummed portion at the apex of said edges, a strip of stronger material than the material of the flap attached to the interior thereof adjacent to said gummed portion, there being 25 an aperture of considerable area in said flap across which one edge of said strip extends, the entire strip being located below the exterior surface of the flap bearing against the body of the wrapper.

Signed at New York city, in the county of New York and State of New York this 1st day of August, A. D. 1912.

HERMAN L. GREVE.
